UNITED STATES PATENT OFFICE.

JOHN MILLER AND ISAAC SMITH, OF HYSON GREEN, COUNTY OF NOTTINGHAM, ENGLAND.

STEAM-WHISTLE.

SPECIFICATION forming part of Letters Patent No. 239,264, dated March 22, 1881.

Application filed January 20, 1881. (No model.) Patented in England July 10, 1880.

To all whom it may concern:

Be it known that we, JOHN MILLER and ISAAC SMITH, both of the firm of Smith Brothers & Co., of Hyson Green Works, Hyson Green, in the county of Nottingham, England, brass-founders and steam-gage manufacturers, have invented new and useful Improvements in Steam-Whistles, (for which we have obtained a patent in Great Britain, No. 2,845, bearing date July 10, 1880,) of which the following is a specification, reference being had to the accompanying drawings.

Our invention relates to improvements in steam-whistles to be employed as danger-signals or fog-alarms, or for locomotives and stationary boilers, and also as signals for indicating the course of ocean or river going vessels. The said invention has more particularly for its object to provide better security 20 against accidents on railways and collisions at sea by producing a variety of distinct signals by the emission of different sounds.

In the new regulations introduced into the "Rule of the Roads at Sea," article 19, option 25 is given to steamers to indicate their course to any vessel which is in sight by whistle-signals. One short blast indicates the course to starboard, two short blasts to port, and three short blasts indicate full speed astern.

Now, the object of our invention is to determine this indication by a variety of distinct sounds, which will be at once understood not only by vessels when in sight, but also during the existence of a fog or other cause which 35 prevents the lights of the vessel being seen, say, on a dark or foggy night.

In the accompanying drawings we have shown various forms or modifications of our improved whistle, which is so constructed that 40 it will give out from one cylindrical bell three or more distinct sounds.

Figure 1 is a front view of a whistle constructed according to the first modification of our improvements and provided with three valve-chambers, and Fig. 1^a a plan of the same; Fig. 2, a sectional view of the said whistle through the center of the right and left hand valves. Fig. 3 is a plan of the valve-chambers, with the front chamber in section. Fig. 4 is a front view of 50 a second modification of whistle having two

valves. Figs. 5 and 6 are a side view and sectional view of a third modification of whistle having one valve. Figs. 7 and 8 are a front view and vertical section of a fourth modification. Fig. 9 is a vertical section of a fifth modification, and Fig. 10 is a horizontal section of a sixth modification with the cap of the cylinder removed. Fig. 11 is a vertical sectional view of a seventh modification, comprising a cylindrical ring-shaped bell or whistle. 55 60

The corresponding parts in each figure are indicated by the same letters where necessary.

A steam-whistle constructed according to our first form or modification consists of the following parts, namely : 65

A is a brass or other metal cylindrical bell, divided vertically into two chambers, as shown in Fig. 2. One chamber is provided with a metal stop, B, which is capable of adjustment, and which serves to regulate the tone or pitch 70 of the sound produced in the said chamber. The upper end of the cylindrical bell has a cap, C, screwed upon it, and near the lower end of the said cylindrical bell the sides are pierced by two unequal perforations, one to each chamber, and the central partition terminates at its lower end in a disk, the circumference of which, with the interior circumference of the cylindrical bell, forms two nearly semicircular slits level with the bottom edges of the unequal perforations. A cylinder so constructed 75 is screwed interiorly at its lower end to connect it to a specially-constructed three-way valve-cock, D, with three screw-threaded valve-plugs, D' D² D³. The valve-chamber D is 80 shown in Fig. 2, the plugs D' D² closed, and in Fig. 3, with the part carrying the plug D³ shown in section.

The dotted circular line D³ in Fig. 2 indicates the position of the valve-seat for the plug D³ 90 with relation to the plugs D' D². Each of the said plugs is provided with a handle at its outer end.

The dotted curved lines in Fig. 3 show the ways through which steam is admitted simultaneously to both chambers in the cylinder upon the plug D³ being opened. 95

This whistle, when attached to a steam-boiler, will produce either two separate tones or a combination of the two tones in the following 100

manner—that is to say: Upon the plug D' being opened steam will pass through the valve in the direction of the arrow shown in Fig. 2 and strike the edge of the chamber to the right, 5 producing the tone peculiar to it, and upon the valve being closed and the valve D² being opened the chamber to the left will produce its tone; and the valve D³ being closed, upon the valve D³ being opened both tones will be 10 blended together and produce one peculiar harmonious sound. The adjustable metal stop-plate B in the chamber enables us to adjust each tone to the greatest nicety, as the lower the stop is adjusted the higher the note will 15 be, and the higher the stop is placed the lower the note will be.

In the second modification, Fig. 4, we have shown a two-chambered whistle which has only two valves, one to each chamber, so that 20 either note may be sounded alone, or both notes sounded at the same time when the said valves are opened. The adjustable stop-plate B is shown by dotted lines in a lower position than in Fig. 2, and will cause a shriller note 25 to be produced. A sectional view of this whistle would be the same as Fig. 2, but without the valve-seat and steamways D³.

In the third modification (shown in Figs. 5 and 6) a two-chambered whistle is shown provided with only one valve, which supplies steam 30 to both chambers at the same time, producing a combination of both notes. The valve is kept closed by a coiled spring on the inclosed end of the valve-spindle D', and is opened by 35 a lever, E, operated by hand or by a rod attached to the upper end of the lever.

The fourth modification (shown in Figs. 7 and 8) consists of a metal cylinder without a vertical division. This cylinder is perforated 40 on one side, the opposite side being of a globular form. The bottom of the said cylinder is screw-threaded to permit its attachment to a steam-chamber having one valve, and of the same construction as that employed in the 45 third modification. The disk only forms a slit extending from one side to the other of the perforation on the front. Above the slit, and within the globular part, is a case-hardened steel shaft, F, the ends of which are free to revolve in screw-threaded bearings F', carried 50 by the sides of the cylinder. The said shaft is T-shaped, and carries a spherical or semi-spherical ball, F², of brass or other metal, which, upon steam being admitted, will cause 55 the shaft to rotate in its bearings and produce a warbling sound. Any or all of the chambers of a steam-whistle may be provided with the ball F² and shaft F.

The fifth modification (shown in Fig. 9) consists of a metal cylinder containing a loose ball, G, kept within the said cylinder by a vertical bar, G', secured to the same by screws. This cylinder is attached by its screw to a valve-chamber, D, similar to that employed in 65 the third modification, and upon steam being admitted and coming in contact with the loose

ball it will rise and fall and give out a warbling or throbbing sound.

The sixth modification of steam-whistle is shown in Fig. 10, which represents a three-chambered cylinder in section attached to a steam-chamber, D, having three valves. One or more of the chambers of the cylinder is provided with an adjustable metal stop to regulate the pitch of the note required. Each valve is fitted with a screw-threaded valve-spindle, as described in the first modification, each being operated by a handle or lever. Upon steam being admitted through the several valves, one, two, or three separate and 80 distinctly different notes may be sounded alone or in combination.

The seventh modification (shown in Fig. 11) consists of a cylindrical ring-shaped bell, A, screw-threaded interiorly at its lower end to 85 permit its connection to a tap, D, having one valve, and similar to that shown in Fig. 5. A loose ball is placed within the ring-shaped bell, and kept within it by a vertical bar, G', secured to the cylinder by screws. Upon 90 steam being admitted to the ball it will revolve within the bell in the direction of the arrows and give out a sound similar to that described with reference to the fifth modification.

Upon the whistles shown in Figs. 1, 2, 3, 4, and 10 we place the words "port," "starboard," and "astern," or their equivalent, according to the language employed. Such words may be stamped, engraved, or otherwise formed upon the handles or levers, or on the valve-chamber or cylinder opposite the handles or levers.

What we claim is—

1. In a steam-whistle, the combination of a 105 stationary bell or sounding-cylinder, divided into two or more longitudinal chambers by one or more fixed partitions, each compartment having a sound-opening with valves arranged to admit steam to said chamber, and a valve 110 to admit steam to two or more of said chambers simultaneously, substantially as described.

2. The cylinder A, provided with two longitudinal chambers arranged to give different tones, in combination with the valves D' and 115 D², arranged to admit steam to said chambers respectively, and the valve D³, arranged to admit steam to both of said chambers simultaneously, substantially as described.

3. The combination, with a sounding-chamber of a steam-whistle, of a ball, F², attached to the laterally-projecting arm of freely-revolving shaft F, journaled in said chamber, and a valve arranged to admit steam to said chamber and to strike said ball, substantially 125 as described, and for the purpose set forth.

JOHN MILLER.
ISAAC SMITH.
